APPARATUS FOR PACKING ROLLS
OF COINS

Jakob Baron, Oppeln, Germany

Application November 20, 1935, Serial No. 50,730
In Germany April 28, 1933

4 Claims.

(Cl. 93—2)

The present invention relates to packing apparatus for packing rolls of coins.

The principal object of the invention is to provide improvements in and novel constructions of apparatus for packing rolls of coins in which a packing paper is used on the two lateral edges of which pointed projecting parts are provided which, after the roll of coins has been rolled up, are folded over on to the ends of the said roll of coins. According to the invention, for the purpose of folding over the pointed projections, there are provided on the two guide rollers receiving the roll of coins, folding rollers, the distance of which from one another is adjustable in a manner known per se according to the length of the roll of coins which is to be packed at any given time, whilst for the purpose of pressing and sticking the pointed projections on to the paper or cardboard discs which are inserted at the ends of the rolls of coins, rollers mounted one above the other on vertical axles between the folding rollers, so as to form roller columns, are employed. For facilitating the adjustment for a definite length of the roll of coins to be packed at any given time, the folding rollers are arranged so as to be displaceable on the guide rollers and are provided with grooves with which a carrier engages, which latter is arranged together with the roller column on an adjustable carriage.

The features of the invention are illustrated by way of example in the constructional form of the apparatus shown in the accompanying drawings, in which:

Fig. 1 is a longitudinal section through the apparatus according to the invention taken on the line A—A of Fig. 3,

Fig. 2 is a corresponding end elevation of the apparatus,

Fig. 3 shows the apparatus in plan,

Fig. 4 is a front elevation of the apparatus,

Fig. 5 shows a cross section taken on the line B—B of Fig. 3,

Fig. 6 shows a cross section taken on the line C—C of Fig. 3,

Fig. 7 is a section taken on the line D—D of Fig. 3 showing the guide rollers in the open position and the inserted packing paper,

Fig. 8 is a similar section showing the guide rollers in the closed position and an inserted roll of coins,

Fig. 9 is a perspective view of a packed and sealed roll of coins, and

Fig. 10 shows a blank of the packing paper employed.

Referring to the drawings:

The packing paper 1 is, as shown in Fig. 10, of approximately rectangular shape and is made of the same width as the length of a roll of coins of a certain definite value. The rear parts of the lateral edges are provided with a row of pointed projections 5, which extend over a length which is equal to the periphery of the roll of coins which it is desired to pack at any given time. The packing paper is also provided at its lateral edges with two circular tongues or lugs 4 having the same diameter as the coins which are to be packed. The circular tongues or lugs 4 may, however, be omitted, and in this case separate circular discs of paper or cardboard are inserted one at each end of the roll of coins, and the projections 5 are folded over and stuck on to the said discs. For this purpose either the lugs 4 or the projections 5 are coated with an adhesive, and the adhesive may be moistened before the packing operation. The said lugs and projections may, however, also be coated with a special adhesive of known kind which is adapted to cause adhesion in the dry state.

The packing paper 1 is also provided with two rows of small apertures or windows 6, which are staggered with regard to one another, in order to render it possible to see through the said windows the coins over the whole width of the paper, i. e. over the whole length of the roll of coins, as can be seen from Fig. 9. Through these apertures it can be seen from the exterior whether the roll actually contains coins and what number of such coins are contained therein.

The apparatus which folds over the projections 5 of the packing paper and sticks it during the rolling up operation against the lugs 4 or against inserted cardboard discs will now be described. The apparatus is preferably arranged on the upper side of a board 7. On the two sides of the board two sheet metal battens 10 are provided which serve for the journaling of the system of rollers comprised by the packing apparatus. In order to provide space for mounting the rollers the front part 11 of the board is recessed and made lower than the middle part 12. The surface of the middle part 12 serves for the reception of the packing paper 1, the projecting lateral sheet metal member 13 serving as a stop to ensure that the paper is in the correct position. The paper passes in the first place through two or more guide rollers 14 and 15. In order to be able to insert the paper 1 easily between the said rollers and thus to bring it into the correct position, the upper roller 14 is arranged so as to be upwardly

adjustable. The axle 15 of the said upper roller 14 is, for this purpose, mounted in a vertical slot 16 as can be seen from Figs. 1 and 2 and Figs. 7 and 8 respectively. Two springs 17 are provided which press the upper roller 14 constantly against the lower roller 13 and in this manner provide a rectilineal guide for the paper 1 during the packing of the roll of coins 9. The rollers 13 and 14 are coated with rubber in order to provide the necessary friction.

It is desirable to be able to effect the upward and downward adjustment with one hand only in order to be able to hold the inserted packing paper 1 in the right position with the other hand until the paper is gripped between the rollers. This is effected by the provision of two small eccentric sectors 20 each provided with a manipulating member 21 and an end stop 22. The two eccentric sectors 20 are positively connected with one another through the medium of an axle 23. If one of the sectors 20 is moved in the direction of the arrow 24 the roller 14 is raised and becomes positioned in the recess 18. When an eccentric sector 20 (Fig. 2) moves back again the axle 15 glides out of the recess 18, and the roller 14 is, in consequence of its being guided by the eccentric sector, drawn down again by spring action.

For the feeding of the roll of coins 9 and for facilitating the rolling of the latter during the packing operation two further rollers 26 operating in known manner are provided. The said rollers carry at one end of each of them stationary folding rollers 27 and are also provided with two folding rollers 28 which are slideable and adjustable upon them and which, during the operation of packing the roll of coins, effect the folding over of the projections 5 of the packing paper 1. The folding rollers 28 must be adjustable to different distances away from the folding rollers 27, inasmuch as it is intended that with one and the same apparatus rolls of coins of any desired different lengths can be packed and sealed. The two folding rollers 28 are therefore mounted so as to be rotatable and slideable on the rollers 26. The sliding movement is effected by means of a carriage 30, which, through the medium of a bearing 31, is slideable on a further roller 33, and which is adapted to be fixed in position by means of a screw 34. The sliding movement is transmitted to the rollers 28 through the medium of a carrier 35 which engages with the grooves 36 of the rollers 28. The length of the roll of coins at any given time is adjusted by means of an indicator 38 associated with a scale 37 which is provided on the front of the surface 11.

For the purpose of packing up the roll of coins the paper 1 is drawn forward. During this movement the inclined edges of the projections 5 strike against the rounded parts of the folding rollers 27 and 28 and are thereby folded upwards so that they finally come to rest on the end surfaces of the roll of coins. The projections 5 are then pressed up against the lugs 4 and stuck on to the latter through the agency of the two vertical roller columns 39 and 40. The roller column 39 is rigidly fixed to the surface 11 of the board and the column 40 is rigidly fixed to the carriage 30. The roller columns each comprise a vertical stationary axle upon which a considerable number of small individual rollers of rigid or resilient material are arranged. The said rollers are adapted to turn individually inasmuch as they are rotated by the end surface of the roll of coins at different speeds from one another. The rounded

portion of the roller column directed towards the end surface of the roll of coins may project slightly in front of the folding rollers 27 and 28 respectively in order to effect the operation of pressing up the projections 5 with certainty. The rollers 27 and 28 are rounded off in order that the surface of the folding roller directed towards the projections 5 may be made as large as possible without contacting with the roller columns 39 and 40 respectively.

It is advantageous to arrange that the setting of the roll of coins 9 which is to be packed, between the roller columns 39 and 40 takes place with a certain amount of spring action. For this purpose the roller 33 together with the carriage 30 is adapted to be displaced axially to a small extent and is provided with an external pressing spring 41.

The method of employing the hereinbefore described apparatus for packing rolls of coins is as follows: The guide roller 14 is first raised by pulling forward the lever 21 in order that the packing paper 1 can be inserted between the two rollers 13 and 14. Thereupon the paper is brought into the position shown in Fig. 3, i. e. so that the projections 5 just touch the sheet metal member 41 and also so that the vertically upwardly flat lugs 4 (Fig. 10) come into position between the roller columns 39 and 40. The roller 14 is then lowered in order that the paper 1 should remain in the correct position. The roll of coins 9 is now laid upon the paper and the rollers 26, whereupon the packing up can be immediately effected by hand. The roll of coins must, during the packing operation, roll on the two rollers 26. After the whole strip of paper 1 has been rolled up the finished, packed and closed roll of coins can be at once taken out of the apparatus.

I claim:

1. In an apparatus for packing rolls of coins, wherein the packing paper employed is provided on its two lateral edges with pointed projections which, when the roll of coins is packed, are folded up against the ends of the roll of coins, the combination of: two guiding rollers receiving the roll of coins; folding rollers arranged on said guiding rollers and adapted to have their distance apart from one another adjusted in a manner known per se; and roller columns comprising rollers located one above the other on vertical spindles between said folding rollers, for pressing and sticking the pointed projections of the packing paper on to discs of material made from paper pulp located at the ends of the roll of coins.

2. In an apparatus for packing rolls of coins, wherein the packing paper employed is provided on its two lateral edges with pointed projections which, when the roll of coins is packed, are folded up against the ends of the roll of coins, the combination of: two guiding rollers receiving the roll of coins; folding rollers arranged on said guiding rollers and adapted to have their distance apart from one another adjusted in a manner known per se; and roller columns comprising rollers located one above the other on vertical spindles between said folding rollers, for pressing and sticking the pointed projections of the packing paper on to circular paper lugs formed integral with the packing paper and located at the ends of the roll of coins.

3. In an apparatus for packing rolls of coins including the combination as specified in claim 1, the improvement consisting in mounting one of said folding rollers in such manner as to be displaceable on said guiding rollers and providing

said folding rollers with grooves with which a carrier engages which is arranged together with one of said roller columns on a carriage.

4. An apparatus for packing rolls of coins, wherein each individual packing paper employed is provided on its two lateral edges with pointed projections which, when the roll of coins is packed, are folded up against the ends of the roll of coins, comprising in combination: a base; journaling means on said base; two guiding rollers journaled in said journaling means and re-

ceiving the roll of coins; folding rollers arranged on said guiding rollers; means—known per se—for adjusting the distance apart of said folding rollers; and roller columns comprising thin rollers mounted on vertical spindles on said base between said folding rollers; said roller columns serving for pressing and sticking the pointed projections of the packing paper on to the ends of discs of material made from paper pulp located at the ends of the roll of coins. 5
